FILLING-REPLENISHING LOOM.

Application filed April 24, 1928. Serial No. 272,382.

This invention relates to filling replenishing looms where a fresh supply of filling is furnished from time to time while the loom continues to run.

5 Looms of the above type are now usually provided with a feeler mechanism for feeling into the shuttle on detecting beats and upon detection of substantial exhaustion of filling to call for replenishment. Where the 10 feeler mechanism and the magazine or hopper are at opposite sides of the loom it has been customary heretofore to part the outgoing filling near the entrance to the replenishing box and position the filling end 15 leading to the cloth selvage for the action of the temple thread cutter, and since the filling leads from the forward end of the shuttle, a long trailing end usually extends from the shuttle eye lengthwise of the shuttle box.

20 The two ends of filling thus produced, one leading to the cloth selvage and the other to the shuttle eye, are liable to be drawn into the shed during subsequent weaving operations, thereby producing imperfect cloth, and many attempts have been made heretofore to obviate this defect. In some cases the end leading to the cloth selvage has been clamped and moved frontwardly by a shuttle feeler thread parter and clamp that it 25 may be positioned for the action of the temple thread cutter during subsequent weaving, but in such cases the filling end leading through the shuttle eye may fail to be withdrawn from the shuttle or shuttle box 30 on replenishment and consequently be carried into the shed on subsequent picks of the shuttle. In other cases attempts have been made 35 to overcome the difficulty by parting the filling adjacent the shuttle eye when it is 40 properly positioned in the replenishing box, so that the short end may pass out of the shuttle and shuttle box with the outgoing filling carrier, and in such cases the long end 45 extending to the cloth selvage has been carried frontwardly in an attempt to remove it from the danger zone and present it to the temple thread cutter. In all of these cases, however, there still remains the danger 50 of one or the other portion of filling ends being carried into the shed owing to various causes incident to the weaving operation.

An important feature of the present invention therefore consists in means for obviating these objectionable conditions by

eliminating both of such ends, or at least, the major portions thereof. In accordance with this feature of the invention, the outgoing filling is parted closely adjacent the selvage of the cloth on call for replenishment of filling as the shuttle passes towards the filling replenishing shuttle box and to effect such parting of the outgoing filling as that there shall be no long end extending from the eye of the shuttle nor an end extending from the cloth selvage.

More specifically stated, the present invention provides a shuttle having a filling thread cutter mounted therein adjacent the delivery end of the shuttle and means which is rendered effective to operate the cutter on call for replenishment of filling and at a point adjacent the selvage of the cloth and also close to the shuttle eye, with the result that both ends of the spent filling are eliminated 75 and danger of weaving imperfect cloth is obviated.

A still further important feature of the present invention consists in means for detecting the presence or absence of filling between the cloth selvage and entrance to the shuttle box following a call for replenishment, and in case the shuttle thread cutter has failed to part the filling to effect loom stoppage that an examination may be made 80 as to the reasons why the cutter has failed to act effectively.

The invention, novel features thereof, and new combination of parts will best be made clear from the following description and the 85 accompanying drawings of one good form thereof.

In the drawings:

Fig. 1 is a front perspective view of a filling replenishing loom containing the present invention, some of the parts being omitted for clearness of illustration;

Fig. 2 is an enlarged side elevation showing more particularly the shuttle thread cutter and in outline indicating the delivery or eye 100 end of the shuttle;

Fig. 3 is a detached plan view of a threading block with which the cutter or cutter and clamp of the present invention may be associated;

Fig. 4 is an underside view of the threading block showing the shuttle thread cutter and clamp and the relation thereof with respect to the side delivery eye;

Fig. 5 is a front end view of the threading 110

block having the cutter and clamp of the present invention;

Fig. 6 is a sectional side elevation through the lay, looking towards the replenishing shuttle box;

Fig. 6^a is a detached detail with parts in section showing more particularly the actuating mechanism for the shuttle thread parter and clamp in its inoperative position;

Fig. 7 is a sectional side elevation showing the actuator for the shuttle thread cutter and clamp in operative position on call for replenishment of filling;

Fig. 8 is a perspective view with parts broken away showing a detector or filling fork mechanism which may be appropriately used as part of the present invention for detecting the presence or absence of filling laid by the shuttle after the operation of the shuttle thread parter and clamp;

Fig. 9 is a plan view similar to Fig. 8, showing the relation of parts of the filling fork mechanism when the latter detects filling laid between the cloth selvage and entrance to the shuttle box after the action of the shuttle thread cutter and clamp; and

Fig. 10 is a slightly modified form showing the active end of the filling fork mechanism which may be utilized in connection with the present invention.

As hereinbefore mentioned, the loom is shown as of the filling replenishing type wherein upon substantial exhaustion of filling in the shuttle a fresh supply of filling may be inserted in the shuttle by the replenishing mechanism. The replenishing mechanism may be of any usual type and since the details of such mechanism form no essential part of the present invention and are now well understood in the art, a full illustration and description thereof is unnecessary.

The loom frame 1 may be of usual construction and extending between the side frames is the breast beam 2. Secured to the loom frame is the hopper or stand 3 containing a number of filling carriers or bobbins 4 having a fresh supply of filling thereon, and associated with the hopper or magazine, which is herein indicated as of the rotary type, is a transfferer 5, whereby on call for replenishment of filling by the filling feeler, as will presently appear, the transfferer 5 is actuated to transfer a fresh filling carrier from the hopper or magazine into the shuttle and to displace or throw out of the shuttle the outgoing or denuded filling carrier or bobbin.

The lay 6 is provided with the usual shuttle boxes 7 and 8, one at each end of the lay, and the shuttle box 8 at the replenishing side of the loom is provided with the usual bottom opening 9 through which the outgoing filling carrier may pass on replenishment of filling. The lay carries the usual reed 10 which is surmounted by the upper or hand rail 11, as more clearly indicated in Figs. 1, 6 and 6^a.

Mounted on the loom frame at the side opposite the magazine or hopper is a filling feeler mechanism to feel for the filling in the shuttle on detecting beats, and when substantial exhaustion of filling is detected the filling feeler mechanism calls for replenishment of filling through a train of mechanism extending to the opposite side of the loom for positioning the dog 12, Fig. 6, which is connected to the arm 13 of the transfferer, so that on call for replenishment of filling by the filling feeler mechanism the dog will be positioned for engagement by a bunter on the lay, as usual, to effect replenishment of filling.

In the present instance of the invention, the filling feeler mechanism consists of a stand 14 mounted at the shipper side of the loom and comprising a filling feeler 15 normally impelled rearwardly by a spring 16 and adapted to enter an opening 17 in the front wall of the shuttle box and a similar opening in the side wall of the shuttle on detecting beats to determine the condition of the filling in the shuttle. The filling feeler mechanism may be of any usual character but as herein shown is substantially the same as the similar mechanism shown and described in the patent to Edward S. Stimpson, No. 1,309,226, dated July 9, 1918, the essentials being that when the filling feeler mechanism detects substantial exhaustion of filling a train of mechanism will be positioned for effecting replenishment of filling when the shuttle reaches the filling replenishing shuttle box. In the construction shown, the transmitter 18, which is associated with the filling feeler, is adapted to operatively position a finger 19 with respect to an operating member 20, which may be the cam follower or a part associated therewith, so that on forward movement of the operating member the arm 21 will be moved forwardly and, through its connection by the arm 22 with the transverse or rock shaft 23, rock said shaft, as usual in this class of looms, for positioning the dog 12 connected with the transfferer for effecting replenishment of filling.

As hereinbefore stated, one of the purposes of the present invention is to avoid the presence of filling ends extending from either the cloth selvage or from the shuttle eye when filling replenishment is to be effected, and to this end the shuttle 24, shown in outline in Fig. 2, is provided with a filling thread cutter and clamp which is to be made effective to part the filling of the outgoing filling carrier at a point adjacent or close to the cloth selvage at the replenishing side of the loom when the filling feeler mechanism calls for a change of filling.

The shuttle 24 may be provided with a threading block 25 having the usual longitudinal extending thread passage, and mounted on the threading block adjacent

the side delivery eye 26 of the shuttle is a stop 27, Fig. 2, which is located directly above the recess 28 which leads to the side delivery eye. Pivotally supported at 29 is the shuttle parter and clamp, the latter of which is normally under the influence of a light spring 30 tending to lift the clamp into engagement with the stop 27. As shown, the clamp comprises the two side members 31 between which is located the thread cutter 32 which may be pivotally supported on the stud 29, as indicated in Fig. 2. The non-cutting portion of the cutter 32 is connected to a link 33 which is pivotally connected at 34 with an arm 35 extending from a plunger 36 which is normally under the influence of a spring 37 tending to hold the plunger in raised position, as indicated in Fig. 2. The spring 37 is stronger than the spring 30 which acts upon the clamping members 31, and a pin 38 extends from the cutter into side recesses formed in the clamping members 31, with the result that the spring 37 normally holds the cutter and the two clamping members in their inoperative position, as indicated in Fig. 2. Pivotally mounted upon the threading block at 39 is the operating finger 40 which extends somewhat above the top of the shuttle and has a downwardly extending free end, as indicated, and the under surface of the operating finger 40 is connected to the plunger 36, with the result that should the operating finger 40 be depressed, the clamping members 31 will be freed to the action of the light spring 30 to first clamp the thread between them and the stop 27 and thereafter the cutter 32 will be operated to cut the thread between the two clamping members and at a point close to the side delivery eye 26 of the shuttle.

As hereinbefore stated, it is desirable to cause the shuttle thread cutter and clamp to operate and part the thread close to the cloth selvage at the replenishing side of the loom on call for replenishment of filling so that after the cutter has operated the shuttle will not deliver any thread thereafter as it approaches the entrance to the filling replenishing shuttle box, the result being that the filling from the outgoing filling carrier will present no objectionable end at the cloth selvage and the end leading from the filling carrier in the shuttle will extend only from the filling carrier to a point inside of the side delivery eye; consequently, on replenishment of filling the outgoing filling carrier will withdraw the short filling end and all danger of either end of filling being carried into the shed will be avoided.

Mounted upon the lay adjacent the cloth selvage is the shuttle thread parter actuator normally inoperatively positioned with respect to the shuttle thread parter but adapted to be operatively related thereto on call for replenishment of filling by the filling feeler

mechanism. As indicated in the drawings, the lay has the bridge piece 41 mounted thereon adjacent the cloth selvage, and, as indicated, the bridge 41 may be attached to the hand rail 11 at its upper end and to the front portion of the lay, as at 42. Pivotally mounted on the bridge-piece at 43 is an arm 44 carrying a projecting lug 45 which constitutes a shuttle thread parter actuator, and the bridge 41 is provided with an opening 46 through which the projection 45 extends.

Connected to the arm 44 at 47 is the link 48 pivotally secured at 49 to a rocker 50 normally under the influence of a spring 51 tending to turn the rocker into the position indicated by Fig. 6^a, thereby normally holding the projection or actuator 45 in its raised or inoperative position. A suitable stop 52 may be utilized to limit the upward movement of the actuator.

The rocker 50 for positioning the shuttle thread cutter actuator may be conveniently mounted upon a stud or dead shaft 53, and the stud or dead shaft may itself be conveniently mounted on a projecting arm 54 secured to the lay. Under the described construction, one end of the spring 51 is secured to the projection 54 and the other end is extended at 55 to bear upon a pin 56 extending from the lower arm 57 of the rocker, the construction being such that the actuator for the shuttle thread parter will normally maintain its upward or inoperative position.

The shuttle thread parter is to be actuated on call for replenishment of filling to cause the shuttle thread parter to part or cut the thread during the flight of the shuttle and at a point closely adjacent the cloth selvage as the shuttle approaches the entrance to the filling replenishing shuttle box.

Mounted on the transverse or rock shaft 23 is the rearwardly extending lifter 58 which normally maintains a lowered position, as indicated in Fig. 6, but when the transverse or rock shaft 23 is rocked in response to the filling feeler mechanism, as is usual, the lifter 58 is raised from the position of Fig. 6 to that of Fig. 7, thereby contacting with the pin 56 on the rocker 50 and turning the rocker from the position indicated in Fig. 7, thereby lowering the actuator for the shuttle thread parter into its operative position, with the result that as the shuttle is picked towards the filling replenishing box the actuator will engage the finger 40 of the shuttle thread parter and actuate the parter to part the thread. The lifter 58 preferably extends rearwardly to a sufficient distance to maintain the actuator in its operative position until the transverse or rock shaft again resumes its normal position following the indication of substantial exhaustion of filling by the filling feeler.

From the construction thus far described it will be apparent that on call for replenishment of filling by the filling feeler mecha-

nism, the actuator for the shuttle thread par-
5 ter will be placed in operative position to ac-
tuate the parter to part or cut the thread at a
point adjacent the cloth selvage as the leading
end of the shuttle emerges from the shed and
10 before it reaches the entrance to the filling
replenishing shuttle box. The result is that
the shuttle will not thereafter deliver thread
and no trailing end of thread will exist be-
15 tween the point where the shuttle thread par-
ter parted or cut the thread adjacent the
cloth selvage and the filling replenishing box.
It will also be apparent that since the thread
20 has been parted inside the shuttle eye, there
will be no trailing end of thread in the re-
plenishing shuttle box, so that on replenish-
ment of filling the outgoing filling carrier will
take with it the end extending into the longi-
25 tudinal thread passage of the threading block.
Thus no trailing end, extending either from
the cloth selvage or from the shuttle eye, will
exist, and consequently all danger of weaving
imperfect cloth due to such trailing end will
30 be avoided.

While the shuttle thread parter or cutter
will ordinarily effectually operate to part or
35 cut the thread, as hereinbefore described, the
present invention provides means for effect-
ing loom stoppage in case the parter fails to
perform its parting or cutting function.
Such failure may be due to the accumulation
40 of lint or the wearing of parts or other con-
tingencies, but in any event, where the shut-
tle thread parter fails to part the thread as
described it is desirable to stop the loom to
examine the cause of such defective action,
45 and to this end the present invention contem-
pates the provision of a detector between the
cloth selvage and the adjacent filling replen-
ishing shuttle box which shall be rendered op-
erative to effect loom stoppage in case the
50 shuttle cutter has failed to cut the thread.

One good form of detector to the above ends
45 consists of a filling fork mechanism located
between the cloth selvage and adjacent the
filling replenishing shuttle box to effect loom
stoppage in case the filling fork mechanism
detects filling after the cutter has operated.

50 Mounted on the loom frame and conven-
iently located at the front of the loom is the
stop shaft 59, Fig. 1, having at its shipper
end the upwardly extending arm 60 carrying
55 a hooked link 61, the hook of which en-
gages over the laterally extending arm 62
of a shipper knockoff 63, the outer end of
which bears against the shipper 64. Simi-
larly extending upwardly from the stop shaft
59 at the opposite side of the loom is a finger
65 which bears upon the front end portion of
60 the filling fork slide 66, the construction be-
ing such that should the filling fork slide 66
be moved forwardly, it will actuate the
stop shaft 59 and cause loom stoppage.

The filling fork slide 66 is mounted upon
65 the guideways 67, Fig. 1, and its rear end

portion has pivotally connected thereto the
filling fork, comprising the head 68 from
which extend downwardly the tines 69. The
filling fork slide is bifurcated at its rear end
portion, as usual, and extending between the 70
bifurcated portions of the slide is a stud or
dead shaft 70 on which is mounted for rock-
ing movement the loop member 71, the rear-
wardly extending end portion 72 of which
projects beneath the head 68 of the filling 75
fork, so that when the filling fork is not tilt-
ed, as indicated in Fig. 10, the loop 71 will
not engage the hook member 72 associated
with the usual cam follower or actuator 73,
the effect being that the filling fork mecha- 80
nism will not effect loom stoppage on the
absence of filling.

Since it is desirable to stop the loom
through the filling fork mechanism when fill-
ing is laid by the shuttle after the action of 85
the shuttle thread parter or cutter, the fill-
ing fork mechanism is under the control of
means associated with the filling fork mecha-
nism. As indicated in Fig. 10, a lever mem-
ber 74 is pivotally mounted on the slide 66 at 90
75 and extending through an opening in the
slide 66 is a pin 76 which underlies the front-
wardly extending loop portion 71 of the fill-
ing fork mechanism. The lever member 74
95 extends forwardly and has a lateral projec-
tion 77, Fig. 1, which overlies the rear end
portion of an arm 78 connected at 79 with
the transverse or rock shaft 23, the result
being that when the filling feeler mech- 100
anism indicates substantial exhaustion of
filling and the transverse or rock shaft 23
is rocked forwardly, the arm 78 lifts the
front end portion of the lever 74 and causes
the pin 76 to drop from its position, indi- 105
cated in Fig. 10, so that the loop 71 is held
in its raised position solely by the filling fork
head 68. Should filling be presented to the
filling fork as the lay moves forwardly
110 after the actuation of the shuttle thread par-
ter or cutter, the filling fork will be tilted,
thereby turning the head 68 of the filling
fork to permit the loop 71 to drop into en-
gagement with the cam follower hook 72, and
thereby effect loom stoppage when filling
115 thread is presented to the filling fork mech-
anism after the operation by the shuttle
thread cutter or parter. It will be apparent
that the filling fork mechanism just de-
scribed does not cause loom stoppage on the
absence of filling but rather on the presence 120
of filling, and such mechanism constitutes a
good form of detector means for determining
whether or not the shuttle thread parter or
cutter has functionally operated on call for
replenishment of filling to prevent the for- 125
mation of trailing ends of filling from the
depleted filling carrier in the shuttle.

It is now the common practice to provide
filling replenishing looms with filling fork
mechanisms to effect loom stoppage in case 130

the filling fails or runs out completely, and this is frequently embodied in what is termed the "double filling fork loom". With this in mind the present invention provides a further filling fork mechanism which during normal weaving operation will effect loom stoppage on failure of filling and will also act to effect loom stoppage on the presence of filling after call for replenishment.

10 The feeler mechanism of the last described type is shown by Figs. 8 and 9 wherein the filling fork slide 66 has pivotally mounted at its rear end the filling fork head 68 provided with the downwardly extending tines 69, 15 similar in all respects to the filling fork head and tines described with respect to Fig. 10. Extending between the side members of the slide 66 is the pin 80 on which is loosely mounted the loop member 81 which when in 20 lowered position, as indicated in Fig. 8, is adapted to engage the cam follower hook 82.

The loop 81 which for identification may be regarded as the "primary" loop, is also provided with a downwardly extending arm 25 83 which has a laterally extended portion 84 underlying the rear end portion of a lever 85 pivoted to the filling fork slide at 86 and under control of the filling feeler mechanism, as will presently appear. Secured to the filling fork head 68 is the arm or lifter 87 having a laterally extending end portion 88 underlying the primary loop 81, the construction being such with the parts in normal position as indicated in Fig. 8 that the filling fork 30 mechanism will be operated to effect loom stoppage on the absence of filling, or, in other words, when the head 68 is not tilted, and consequently the arm 87 fails to lift the primary loop 81. The mechanism now acts 35 as an ordinary filling fork mechanism to stop the loom on the absence or failure of filling.

40 Loosely mounted upon the stud 80 is the secondary loop 89 having a rearwardly extending end portion or projection 90 which underlies the head 68 of the filling fork.

The lever 85 has a laterally extending pin 45 91 which overlies the arm 78 which, as before explained, is secured to the transverse or rock shaft 23 and consequently under control of the filling feeler mechanism. With the parts as indicated in Fig. 8, should the filling fork be tilted by the presence of filling, the arm 87 will lift the primary loop 81 so that it will not engage the cam follower hook 82, but should it fail to be tilted by the absence of filling the primary loop 81 will engage the cam follower hook 82 and the loom will be stopped as usual.

50 60 When the filling feeler mechanism indicates substantial exhaustion of filling and the arm 78 turns the lever 85 into the dotted line position of Fig. 9, the rearwardly extending arm of this lever presses upon the lateral projection 84 of the primary loop 81,

and such primary loop will be thrown out of action. Should filling be presented to the filling fork at this time, the filling fork will be tilted, with the result that the secondary loop 89 will drop into the path of the cam 70 follower hook 82 and effect loom stoppage, a condition which is indicated in Fig. 9. Thus the filling fork mechanism last described will act to effect loom stoppage during weaving operations on the absence of filling, and, 75 when the filling feeler mechanism calls for a change of filling the weft fork mechanism will effect loom stoppage on the presence of filling.

80 As usual in connection with filling fork mechanisms, the lay carries or may carry a grid, such, for instance, as indicated at 92, Fig. 9, wherein it will be noted that the filling fork has been tilted by the filling *a* in front of the grid as the lay moves frontwardly after 85 call for replenishment of filling.

85 From the construction described it will be apparent that the present invention provides cutting mechanism for cutting the spent filling close to the cloth selvage upon call for 90 replenishment of filling by the filling feeler mechanism, and such cutting of the filling is accomplished at the eye of the shuttle during 95 its pick before it enters the filling replenishing box, so that the shuttle is prevented from thereafter laying filling between the cloth 100 selvage and entrance to the shuttle box and all trailing ends are eliminated. It will also be observed that the present invention provides means for detecting the presence or 105 absence of filling following a call for replenishment of filling and the operation of the shuttle thread cutter, and in case the filling fails to be cut to effect loom stoppage.

110 What is claimed is:

1. In an automatic filling replenishing loom, the combination of the lay and shuttle boxes, a shuttle provided with a filling thread cutter carried by the shuttle, a cutter actuator adjacent the cloth selvage and rendered effective on call for replenishment of filling to cause the shuttle thread cutter to part the filling at the instant the shuttle eye is adjacent the cloth selvage and thereafter prevent delivery of thread by the shuttle between the 115 cloth selvage and entrance to the shuttle box.

120 2. In an automatic filling replenishing loom, the combination of the lay and shuttle boxes, a shuttle provided with a filling thread cutter, a cutter actuator rendered effective on call for replenishment of filling to cause the shuttle thread cutter to part the filling adjacent the cloth selvage and thereafter prevent delivery of thread by the shuttle between the 125 cloth selvage and entrance to the shuttle box, and means for effecting loom stoppage should the shuttle thread cutter fail to part the thread.

130 3. In an automatic filling replenishing loom, the combination of the lay and shuttle

- boxes, a shuttle provided with a filling thread cutter carried by the shuttle, a cutter actuator mounted on the lay adjacent the cloth selvage and means rendered effective on call for replenishment of filling to operatively position the cutter actuator and cause the shuttle thread cutter to part the filling adjacent the cloth selvage and thereafter prevent the formation of an end of appreciable length extending from the cloth selvage by preventing delivery of thread from the shuttle between the cloth selvage and entrance to the shuttle box.
4. In an automatic filling replenishing loom, the combination of the lay and shuttle boxes, a shuttle provided with a filling thread cutter, a cutter actuator mounted on the lay between the entrance to the shuttle box and cloth selvage and rendered effective on call for replenishment of filling to cause the shuttle thread cutter to part the filling adjacent the cloth selvage and thereafter prevent delivery of thread by the shuttle between the cloth selvage and entrance to the shuttle box, and means for stopping the loom should the shuttle thread cutter fail to part the thread.
5. In a filling replenishing loom, the combination of the lay and shuttle boxes, a shuttle provided with a filling thread cutter carried by the shuttle, a cutter actuator mounted on the lay adjacent the cloth selvage and rendered effective on call for replenishment of filling to cause the shuttle thread cutter to part the thread adjacent the cloth selvage before the shuttle wholly passes from the shed that filling may not thereafter be delivered by the shuttle between the cloth selvage and entrance to the shuttle box and form an end of appreciable length extending from the cloth selvage.
6. In a filling replenishing loom, the combination of the lay and shuttle boxes, a shuttle provided with a filling thread cutter, a cutter actuator mounted on the lay between the entrance to the shuttle box and cloth selvage and rendered effective on call for replenishment of filling to cause the shuttle thread cutter to part the thread adjacent the cloth selvage before the shuttle wholly passes from the shed that filling may not thereafter be delivered by the shuttle between the cloth selvage and entrance to the shuttle box, and means for stopping the loom should the shuttle deliver thread after operation of the shuttle thread cutter.
7. In an automatic filling replenishing loom, the combination of the lay and shuttle boxes, a shuttle provided with a filling thread cutter, a cutter actuator mounted on the lay between the entrance to the shuttle box and cloth selvage and rendered effective on call for replenishment of filling to cause the shuttle thread cutter to part the filling adjacent the cloth selvage and thereafter prevent the delivery of thread by the shuttle between the cloth selvage and entrance to the shuttle box, and detector mechanism between the cutter actuator and shuttle box for stopping the loom should filling be laid by the shuttle between the cloth selvage and shuttle box after the shuttle cutter actuator has operated.
8. In a filling replenishing loom, the combination of the lay and shuttle boxes, a shuttle provided with a filling thread cutter, an actuator for causing the shuttle thread cutter to part the filling on call for replenishment of filling, a detector between the actuator and shuttle box for detecting the presence or absence of filling, and means for causing the detector to effect loom stoppage when filling is detected between the cloth selvage and shuttle box on the beat up movement of the lay immediately following a call for replenishment of filling.
9. In a filling replenishing loom, the combination of the lay and shuttle boxes, a filling feeler for initiating replenishment when the filling in the shuttle is substantially exhausted, a shuttle provided with a filling thread cutter, a cutter actuator rendered effective on call for replenishment of filling to cause the shuttle thread cutter to cut the thread adjacent the cloth selvage at the replenishing side of the loom, a detector between the cutter actuator and entrance to the shuttle box, and means for stopping the loom should filling thread be detected between the cutter actuator and entrance to the shuttle box following a call for replenishment of filling.
10. In a filling replenishing loom, the combination of the lay and shuttle boxes, a filling feeler for initiating replenishment when the filling in the shuttle is substantially exhausted, a shuttle provided with a filling thread cutter, a cutter actuator rendered effective on call for replenishment of filling to cause the shuttle thread cutter to cut the thread adjacent the cloth selvage at the replenishing side of the loom, a filling fork mechanism between the cloth selvage and filling magazine, and means controlled by the filling feeler to cause the filling fork mechanism to effect loom stoppage when the filling fork is tilted by the presence of filling following a call for replenishment.
11. In a filling replenishing loom, the combination of the lay and shuttle boxes, a filling feeler for effecting replenishment of filling when the filling in the shuttle is substantially exhausted, means for parting the filling at the cloth selvage remote from the filling feeler upon call for replenishment, a filling fork mechanism between the cloth selvage and replenishing shuttle box, and means controlled by the filling feeler to cause the filling fork mechanism to effect loom stoppage.

page when the filling fork mechanism detects the presence of filling following a call for replenishment by the filling feeler.

12. In a filling replenishing loom, the combination of the lay and shuttle boxes, a filling feeler to feel for the filling in the shuttle and on substantial exhaustion thereof to call for replenishment, a shuttle provided with a filling thread cutter, means for causing the shuttle thread cutter to part the filling adjacent the cloth selvage remote from the filling feeler on call for replenishment, a weft fork mechanism between the selvage and replenishing shuttle box, and means controlled by the filling feeler to cause the weft fork mechanism to effect loom stoppage when filling is presented to said mechanism following an operation of the shuttle thread cutter.

13. In a filling replenishing loom, the combination of the lay and shuttle boxes, a filling feeler to detect the condition of the filling in the shuttle on detecting beats and call for replenishment when the filling is substantially exhausted, means for parting the filling adjacent the cloth selvage at the replenishing side of the loom on call for replenishment by the filling feeler, a filling fork mechanism between the replenishing shuttle box and the adjacent cloth selvage, loom stopping means adapted to be operated by said mechanism and means between the filling feeler and filling fork mechanism to render the latter operative to effect loom stoppage when filling presence is detected by the filling fork mecha-

nism following an operation of said parting means.

14. In a filling replenishing loom, the combination of the lay and shuttle boxes, a shuttle provided with a filling thread cutter and clamp carried by the shuttle and including clamping members between which the thread passes as it is delivered from the side delivery eye, an operating member for the cutter and clamp normally under the influence of yielding means to maintain the cutter and clamp in an inoperative position, an actuator carried by the lay and rendered effective on call for replenishment of filling for causing the clamping members to clamp the thread and then the cutter to part the thread after the thread has been clamped in the shuttle.

15. In a filling replenishing loom, the combination of the lay and shuttle boxes, a filling feeler to feel for the filling in the shuttle and call for replenishment on substantial exhaustion of filling, means for cutting the filling adjacent the cloth selvage at the replenishing side on call for replenishment, a filling fork mechanism normally operative to stop the loom on filling failure, and means controlled by the filling feeler to cause the filling fork mechanism to stop the loom on presence of filling after an operation of the cutting means.

In testimony whereof, I have signed my name to this specification.

ARTHUR W. BEARDSELL.
